US0D1089809S

(12) **United States Design Patent** (10) **Patent No.:** **US D1,089,809 S**
(45) **Date of Patent:** **** Aug. 19, 2025**

(54) **LAMP**

(71) Applicant: **ZHONGSHAN FENGCYI
TECHNOLOGY CO., LTD,**
Zhongshan (CN)

(72) Inventor: **Shiqiang Yuan**, Zhongshan (CN)

(73) Assignee: **ZHONGSHAN FENGCYI
TECHNOLOGY CO., LTD,**
Zhongshan (CN)

(**) Term: **15 Years**

(21) Appl. No.: **29/893,984**

(22) Filed: **Jun. 5, 2023**

(51) LOC (15) Cl. **26-05**
